UNITED STATES PATENT OFFICE

MILTON T. CLARK AND JOHN RUSSELL MONTGOMERY, OF YOUNGSTOWN, OHIO, ASSIGNEES TO TRUSCON STEEL COMPANY, OF YOUNGSTOWN, OHIO, A CORPORATION OF MICHIGAN

WINDOW FRAME

Application filed November 23, 1928. Serial No. 331,468.

The object of the present invention is to provide a window structure, preferably formed of rolled sheet metal elements, and in which glass-carrying frames are employed 5 mounted in the sashes and capable of lateral movement for the purpose of giving ventilation and also making the outer sides of the panes accessible within the room for the purpose of cleaning. A further and important 10 object is to provide a structure of relatively simple character in which the glass-carrying frames will be maintained wherever placed.

In the accompanying drawings:—

Figure 1 is a perspective view of the preferred embodiment of the invention and showing the glass-carrying frames in various positions.

Figure 2 is a vertical sectional view through the window structure with the sashes 20 and transom closed.

Figures 3 and 4 are cross sectional views on the line 3—3 and 4—4 of Figure 2.

Figure 5 is a perspective view of one of the pivot and holding devices.

In the embodiment disclosed a window frame is provided that is preferably formed of sheet metal, and includes a sill member 6 having an upstanding abutment rib 7 for the lower sash. The sides of the frame are 30 in the form of boxes 8, in which the usual weights indicated at 9 in Figure 3 reciprocate. The sides include plates 10 located on the inner sides of the boxes 8 and these plates have longitudinal guide slots 11. They are 35 furthermore provided with channeled members 12 that serve also as guides. In the present structure a tubular rail formed of sheet metal sections and designated 13 divides the frame into an upper transom opening 14 and a lower window opening 15. A transom is shown at 16, said transom being pivoted at its lower end as illustrated at 17, whereby it may be swung inwardly. A latch 18 serves to hold the transom in its closed position. In 40 the window opening 15 are cooperating vertically sliding sashes 19 and 20. As these sashes are substantially alike in structure, a description of one it is believed will be sufficient for both, the material differences being 45 later pointed out.

A sash frame is provided formed of substantially Z-shaped bars, both stiles and rails having body strips 21 with outstanding flanges 22 along their inner edges and inwardly extending flanges 23 along their outer edges. It will be noted by reference to Figures 3 and 4 that the outstanding flanges 22 travel in the guide channels 12. Fixed to the outer sides of the body strips 21 of the stiles are angle bars or strips 24, the outstanding flanges of which travel in the guide slots 11 of the plate 10. It will thus be evident that the sashes are guided vertically in the window frame. The bottom rail of the upper sash has its upstanding flange 22 inset at an inclination, as shown at 25, and the top rail of the lower sash has secured upon it a strip 26 provided with a downturned inclined portion 27 that overlies the portion 25. When the sashes are closed (see Figure 2) the downturned flange 23 of the bottom rail of the lower sash 20 depends over and alongside the upstanding portion 7 of the sill 6. The top rail of the upper sash 19 has fixed to it an angle bar 28 that enters a groove 29 formed by the downturned terminal flanges 30 of the main frame rail 13. Thus interfitting portions are provided between the two sashes and between the two sashes and the window frame, that serve to prevent the entrance of air and water.

In each of the sashes 19 and 20 is mounted a laterally movable glass-carrying frame, and as the frames in both instances are the same, a description of one will do for both. Each sash-carrying frame consists of substantially Z-shaped bars or strips comprising a body portion 31 with an outstanding flange 32 along its inner edge and an inset flange 33 along its outer edge. The latter flange is bent inwardly as shown at 34 to provide a putty-receiving channel 35. The glass pane is shown at 36 and is held behind the flange 33—34 by an angle strip 37 placed behind the glass and secured to the body portion 31. It will be noted that the glass-carrying frame is so related to the sash frame that the flanges 33 of the former abut the flange 23 of the latter and that the flange 32 of said glass-carrying frame abuts the flange 22 of the sash frame when 50

the glass-carrying frame is in its closed position or fitted within the sash frame.

The glass-carrying frame has pivoted to its stiles and as shown at 38 the lower ends of links 39, the pivots 38 being preferably located below the centers of said stiles. The upper ends of the links 39 are pivoted to the inner sides of the upper ends of the sash-carrying frames, as shown at 40. The lower 10 end of the glass-carrying frame has a sliding pivotal mounting in the sash frame. To this end there are secured to the inner sides of the lower portions of the stiles of said sash frames vertical channel bars 41. The lower rails 15 of the glass-carrying frame have secured thereto angle bars 42 which form with the flanges 32 a channel 43. In this channel are secured spring-pressed plungers (see Figure 5 for the detail thereof). A U-shaped frame 20 44 is secured in the channel 43, thus providing spaced downturned ears 45 and in said ears is a reciprocatory plunger 46 having a cylindrical head 47 that engages in one of the guide channel bars 41. On the shank of the plunger 25 46 is a coiled spring 48 that abuts against the rear ear 45 and against a shoulder 49 formed on the shank. The spring thus urges the plunger outwardly and causes the free end of its head to frictionally bear with considerable pressure against the bottom of the channel guideway 41. There being two of these plungers, it will be evident that they 30 project from the opposite lower corners of the sash-carrying frame and constitute not only pivots on which the said frame swings, but also act as sliding frictional bearing members in the sash frame. It will be noted by reference to Figure 2 that when the glass-carrying frame is in its closed position, the 35 lower flange 32 depends on the outer side of and against the upstanding flange 22 of the sash frame and that the depending flange 42 of the glass-carrying frame depends on the outer side and against the flange 23 of the sash frame. A tight joint is thus obtained. The upper end of the glass-carrying frame can be secured to the sash frame by any suitable means, as for instance a rotary latch 50 mounted on the upper end of the glass-carrying frame and having a nib 51 that interlocks with the upper rail of the sash frame. A suitable detachable handle shown at 52 in Figure 1 can be used for turning this latch.

With this construction, when the sash carrying frames are closed and locked, both upper and lower sashes may be raised or lowered in the usual manner. If it is desired to open either or both of the windows for 60 ventilating purposes and without raising the sashes, it is only necessary to unlock and draw the glass-carrying frames inwardly. This causes the upper ends of said frames to swing inwardly, while the lower rails turn 65 on the pivot axes of the heads 37 and thus the

flanges 32 and 42 will swing away from the flanges 22 and 23 and rise above the same. The glass-carrying frames can be positioned as desired and as indicated in Figure 1, their positions being maintained by the spring 70 plungers frictionally engaging the bottoms of the channel pieces 41 and holding the frames against accidental movement.

From the foregoing, it is thought that the construction, operation and many advantages 75 of the herein described invention will be apparent to those skilled in the art without further description and it will be understood that various changes in the size, shape, proportion and minor details of construction may 80 be resorted to without departing from the spirit or sacrificing any of the advantages of the invention.

What we claim is:—

1. In a window structure, the combination 85 with a window frame, of a sash frame slideable therein, a glass-carrying frame including top and bottom rails, one of which is provided with an open ended channel, links pivoted to the sash frame and to the glass-carrying frame, guideway on the stiles of the sash frame, and spring-pressed plungers located longitudinally of and housed in the ends of the channel of said channelled rail of the glass-carrying frame and slidably extending through the open end of the channel and 90 engaged in the guideways of the sash frame's stiles.

2. In a window structure, the combination 100 with a sash frame including a rail having spaced flanges, of a glass-carrying frame including a rail having spaced flanges that slidably overlap the flanges of the sash rail, said flanges of the rail of the glass-carrying frame forming an open-ended channel between them, links pivoted to the sash frame and to the glass-carrying frame, guideways on the stiles of the sash frame, and spring-pressed plungers located longitudinally of 105 and housed in the channel of said rail of the glass-carrying frame and having their ends extending through the open ends of the channel and slidably engaged in the guideways of the sash frame's stiles.

3. In a window structure, the combination 115 with a window frame, of a sash frame slideable therein and having a bottom rail provided with an inner upturned flange and an outer downturned flange, said sash frame having stiles provided with channelled guideways on their inner sides, a glass-carrying frame that fits into the sash frame and includes a bottom rail provided with spaced depending flanges forming a channel between them, said flanges depending on the outer sides of the flanges of the said sash frame rail, links pivoted to the upper portions of the stiles of the sash frame and to intermediate portions of the stiles of the glass-carrying frame, and spring-pressed 120 125 130

plungers located longitudinally of and in the channel of the rail of the glass-carrying frame and projecting into and frictionally engaging the guide channels of the stiles of the sash frame.

5 4. In a window structure, the combination with a sash frame having a stile provided with an inset outer flange and a guideway behind the flange, a glass carrying frame 10 having a stile that abuts against the flange and having an inner outstanding flange that abuts the sash stile, forming a boxing for the guideway, said sash carrying frame having a channeled cross rail, and a spring pressed 15 plunger located longitudinally of and housed in the channel of the rail and having a head slidable in the guideway of the sash stile.

5. In a window structure, the combination with a sash frame having a stile provided 20 with an inset outer flange and a longitudinal guideway behind the flange at one end of the stile, a glass carrying frame having a stile that abuts against the flange and having an inner outstanding flange that abuts the 25 sash stile forming a boxing for the guideway, a link pivoted to both stiles at one end of the guideway and enclosed by the flanges of the stiles, said sash carrying frame having an open-ended channeled rail, and a 30 spring-pressed plunger housed in the channel of the rail and having a head extended through the open end and slidable in the guideway of the sash stile.

In testimony whereof, we affix our signatures.

MILTON T. CLARK.

JOHN RUSSELL MONTGOMERY.
